ATTORNEY.

INVENTOR.

UNITED STATES PATENT OFFICE.

GEORGE LEFEBVRE, OF LAWRENCE, MASSACHUSETTS.

DETACHABLE HOLDER.

Application filed January 26, 1928. Serial No. 249,578.

This invention relates to quickly detachable supporting devices and especially to window shade holders such as are used to support the trunnion on each end of a roller window shade.

Its purpose is to provide such a holder which can be quickly sprung or snapped on to the wooden casing around a window or door, or on to a chair rail or a closet rail, and which has claws which fit into the wood and keep the holder in place.

My device can be easily and cheaply made as it can be stamped from a single sheet of elastic metal.

15 It is a great advantage of my device when used as a window shade hanger that it can be instantly snapped on or off the sides instead of the top of a window casing, and its claws will hold it firmly in any position and 20 that its shade bracket is so elastic that shades of different lengths can be supported between the same two brackets.

In the drawings, Fig. 1 is an elevation of a window or door casing with my preferred 25 form of device in place.

Fig. 2 is a sectional view looking down on line 2—2 of Fig. 1.

Fig. 3 is a plan view of my device before attaching.

30 Fig. 4 is a view similar to Fig. 2 of a modification.

Fig. 5 is a vertical sectional elevation of a chair rail with a modification of my device in place.

35 Fig. 6 is a plan view of another modification in place.

Fig. 7 is an elevation shown on a reduced scale of a modified device used as a coat or utensil hook attached to the side frame of 40 a door.

Fig. 8 is an elevation and Fig. 9 a plan view of a modification to be used as a brush or broom support.

45 Fig. 10 is a plan view of another modified brush support.

In the drawings, A represents a wooden casing such as are on each side of a window. It has the sides 10 and 11 and front 12.

50 B represents a shade roller of a common construction having at each end trunnions such as 2. One of these is generally round and the other squared.

C is my holder which is formed of an elastic sheet of metal bowed outwardly and

bent at each end 20 and 21 inwardly to form 55 claws 22 and 23 which when the middle part 19 is straight are substantially parallel with each other and terminate in points 24 and 25, which under such conditions point substantially towards each other.

Near the middle part, cut or stamped from the metal at 26 is a shade bracket F bent outwardly and having near its free end a passage 30 for a trunnion such as 2 for a shade roller.

60 As shown by the dotted lines in Fig. 2, this bracket being elastic will give to accommodate rollers of different lengths. 29 is a lifting tab stamped from the metal.

In Fig. 4, I show a bracket G which is 70 bent out at substantially right angles.

In Fig. 5, I show how by a slight modification, my device can be used as a coat hook, brush hook or for any purpose where a supporting projection is desired. H represents 75 a chair rail or a rail such as is used in closets of oblong cross section, having front 40, back 41 attached to wall 42, top 43, and bottom 44.

K is my holder made of elastic sheet metal 80 bowed out at 50 and having at each end, the curved prongs or claws 51 and 52 which point substantially towards each other. 53 is a supporting projection preferably stamped out of the material and bent to 85 form a hook.

In Fig. 6, I show a holder L bowed at 60, and with claws 61 and 62 while 63 and 64 are curved arms which extend out therefrom so formed that they will receive and frictionally hold an article like a brush having a round handle such as 66.

The lifting tab 29 is a great convenience especially in removing my device from position.

95 As shown in Fig. 4, by forming bracket G on one side of the middle of C, longer or shorter curtain shades such as B can be accommodated, merely by turning the holder end for end.

In Fig. 7 holder 70 has claws 71 which hold it to frame A and has a hook 72 stamped out of its body.

100 Figs. 8 and 9 show a sheet metal bowed elastic body 80 having claws 81 and 82 and supporting projections 83 and 84 stamped from body 80.

Fig. 10 shows a body 90 with claws 91 and

92 and projections 93 and 94 of a slightly different shape, shown as not stamped but attached to body 90 by rivets 95, 95.

I claim:

5. 1. A shade holder formed of elastic sheet metal bowed outwardly and bent inwardly at each end to form claws each terminating in points which point substantially towards each other and having a shade bracket 10 stamped from the metal and bent outwardly, together with a lifting tab also stamped from and bent outwardly from the metal.
- 10 2. A holder formed of elastic sheet metal bowed outwardly and bent inwardly at each 15 end to form claws each terminating in points which point substantially towards each other and having a supporting projection stamped from the metal and bent outwardly, together

with a lifting tab also stamped from and bent outwardly from the metal.

20

3. A holder formed of elastic sheet metal bowed outwardly and bent inwardly at each end to form claws which point substantially towards each other and having a supporting projection stamped from the metal and bent 25 outwardly.

4. A window shade holder formed of elastic sheet metal bowed outwardly and bent inwardly at each end to form claws which point substantially towards each other and having a supporting projection stamped from the metal and extending outwardly so that its free end is substantially at one side of the middle line between said claws.
